UNITED STATES PATENT OFFICE.

JUNIUS BRUCE HATHAWAY AND ALFRED REGINALD McDIARMID, OF BRANDON,
MANITOBA, CANADA.

STEERING TONGUE.

Application filed April 15, 1922. Serial No. 552,921.

To all whom it may concern:

Be it known that we, JUNIUS BRUCE HATHAWAY and ALFRED REGINALD McDIARMID, subjects of the King of Great Britain, and residents of the city of Brandon, in the Province of Manitoba, Canada, have invented certain new and useful Improvements in Steering Tongues, of which the following is the specification.

10 The invention relates to improvements in tongues and particularly to a steering tongue and as utilized on plows and such like agricultural implements and an object of the invention is to provide a steering tongue arranged and constructed so that it is not apt to be broken by the draft animals, as at present where stiff tongues are used.

With the above more important object in view the invention consists essentially in a tongue formed from pivotally connected front and rear sections and a spring restraining the swinging movement of the front section, the parts being arranged.

Fig. 1 is a side view of the tongue as it appears attached to a plow.

Fig. 2 is an enlarged detailed side view of a portion of the tongue.

Fig. 3 is an inverted plan view of a portion of the tongue.

30 Fig. 4 is a vertical sectional view through the tongue at 4-4' Fig. 2.

In the drawing like characters of reference indicate corresponding parts in the several figures.

35 This tongue is particularly constructed for attaching to plows or such like agricultural implements.

The plow indicated generally by the reference numeral 1, is drawn by the draft animals which are hitched to the head 2 of the plow. The plow is steered by a steering tongue having the rear end connected to the spindle 3, which is provided at the lower end with a wheel 4.

45 The steering tongue which we provide is formed from a front section 5 and a rear section 6. The rear end of the rear section is connected in the usual manner by a swivel joint 7 to the upper end of the spindle 3, whilst the forward end of the front section is provided on the underside with the customary neck yoke stop 8.

55 It will be observed that the rear end of the front section of the tongue underlies the forward end of the rear section and that the

forward end of the rear section is provided with a vertically disposed pivot bolt 9, which supports swivelly a stirrup or double eared hanger 10. This hanger spans the tongue 5 and is connected to the latter 60 tongue by a horizontally disposed pivot bolt 11 passing through one of a number of adjusting openings 12 provided in the tongue 5.

According to this arrangement it will be obvious that the tongue section 5 can swing laterally or vertically according to the circumstance. To the rear end of the tongue section 5 we connect a spring 13, the rear end of which is attached by means of a link 14 to an eye 15, located rearwardly of the tongue section 6 and on the underside thereof. This spring acts to restrain to a limit of extent, the swinging movement of the front tongue section and normally maintains the tongue sections in parallelism. 75

The tongue which we provide, and as hereinbefore described, will operate to steer the plow in the same manner as the ordinary stiff tongue, but by providing the swivel joint and spring there is practically no possibility of the tongue becoming broken such as by the draft animals treading on it or crowding it. Obviously, if the animals crowd too heavily on the front end of the section 5 it will swing laterally, and should a draft animal step on the tongue it will break joint downwardly or in the manner shown in dotted outline in Fig. 1.

What we claim as our invention is:

1. In a steering tongue, a rear tongue section and a forward tongue section, the rear end of the forward section passing to the rear of the front end of the rear section, a pivot fastening connecting the forward end of the rear section to the adjoining portion of the front section, said pivot fastening permitting of the lateral and vertical swinging of the front section and a spring yieldingly connecting the rear end of the front section to the rear part of the rear section. 90

2. In a steering tongue, a rear tongue section, a front tongue section, the rear end of the front section underlying the forward end of the rear section, a pivot bolt extending vertically through the forward end of the rear section, a stirrup carried by the bolt and spanning the front section, a horizontally disposed pivot bolt carried by the stirrup and passing through the front tongue 110

section and a spring connecting the rear end of the front section to the rear part of the rear section.

3. A steering tongue comprising normally aligned sections and connecting means swiveled to one connection and having hinge connection with the other section.

4. A steering tongue comprising front and rear sections, a bracket swivelled to one section and a removable hinge pin supported by the bracket and passing through one of a plurality of holes formed in the remaining section.

5. A steering tongue comprising a pair of

sections, means hingedly and swivelly connecting the sections together to permit independent vertical and lateral movement of one section and yielding means normally maintaining the sections in substantial alignment.

Signed at Brandon, Man., this 27th day of March, 1922.

JUNIUS BRUCE HATHAWAY.
ALFRED REGINALD McDIARMID.

In the presence of—

A. H. RENN,
H. A. McNEILL.
